CHASE

Gilbert H. Higgins, Mountain Lakes, N. J., assignor to R. Hoe & Co., Inc., New York, N. Y., a corporation of New York; Irving Trust Company, permanent trustee

Application February 20, 1932, Serial No. 594,177

14 Claims. (Cl. 101—17)

This invention relates to printers' chases, having for its principal object the provision of a novel chase that will obviate the necessity of having two separate chases or forms, one thick for protecting the type when a matrix is to be made, the other thin for obtaining a proof.

Another object is to provide a combination chase suitable for preparing a matrix, from type forms secured therein, and then convertible to a chase adapted for obtaining a proof from the same type forms.

It is also an object of the invention to provide a chase of generally improved construction, whereby the device will be simple, durable and inexpensive in construction, as well as convenient, practical, serviceable and efficient in its use.

In the printing art it is customary to provide a chase for holding printing forms from which stereotype matrices are prepared, with a thicker frame than the frame of the chase employed directly for printing. This is necessary by reason of the fact that when the matrix is rolled or pressed into the type, it is necessary to support the type close to the upper surface of the chase in the normal horizontal position shown in Figure 2, in order to prevent battering down the type that is adjacent to the sides and edges of the form. While the thick chases protect the type when a matrix is to be made, they cannot be used for printing as the chase itself would be inked simultaneously with the type and print a black border around the page or matter printed on. It is common practice to place the form in the thick chase to make a matrix and then to transfer it to a thin chase for obtaining a proof. The present invention is designed and adapted to eliminate this transfer operation as the base portion holds the form for the printing operation, while means forming one of the features of the present invention are placed on top of the base portion when the matrix is to be made.

Other objects and advantages will appear hereinafter and will be best understood when taken in connection with the accompanying drawing, in which:

Figure 1 is a perspective view, with parts broken away, of an embodiment of my invention as it appears in position for preparing a matrix;

Figure 2 is a sectional view, partly in elevation, taken on line 2 of Figure 1, showing type forms arranged within the frame.

For the purpose of illustrating my invention I have shown in the accompanying drawing one form thereof which is at present preferred by me, since the same has been found in practice to

give satisfactory and reliable results, although it is to be understood that the various instrumentalities of which my invention consists can be variously arranged and organized and that my invention is not limited to the precise arrangement and organization of the instrumentalities as herein shown and described.

In the drawing, 10 designates a frame or base within which a quoin 11, a coacting side or locking bar 12, and a foot bar or stick 13 are slidably and adjustably mounted. The quoin 11 is formed or provided with coacting wedge surfaces 11' which coact with corresponding wedge surfaces 12' on the side bar 12, whereby when the quoin 11 is slid longitudinally by means of an adjusting screw 14 connected thereto and threadedly secured in the foot of the frame 10, the side or locking bar 12 will be moved laterally or inwardly into operative engagement with type bodies or forms 15 in the frame or moved outwardly to unclamp the said type bodies.

The foot bar 13 is provided with a plurality of pockets 16, receiving the stems of adjusting screws 17 threadedly engaged in the lower portion of the frame, and is slidably mounted within the frame 10. Each of the adjusting screws 17 is freely rotatable within a pocket 16 and is confined therein by a screw 18, fastened in the bottom of bar 13, the end of said screw 18 being seated in an annular groove 19 formed on the stem of the adjusting screw 17. The foot bar 13, as will be observed, is of a length suitable for permitting the lateral or inward movement of the side bar 12 when engaging type forms.

As an important feature of the present invention, a plate, cover or cap member 21 is detachably secured to the frame 10 in any suitable manner as by dowel pins 22 fastened to the plate 21 and received in sockets 22' provided in the frame 10. The inner margin of the cover member 21 is formed with an undercut portion or groove 21' adapted to receive the bolster or marginal projection of a matrix and a registering tongue or projection 23 on a plate or cover member 24 detachably fastened to the foot bar 13 by dowel pins 25 secured to the last mentioned plate 24 and also received in sockets 25' in the foot bar 13, or in any other suitable manner. The plate 24 on the foot bar 13 is also formed with an undercut portion or groove 24' also adapted to receive the bolster or marginal projection of a matrix, and has its upper surface flush with the top of the plate or cover member 21 mounted on the frame 10.

It will now be understood that when the cover

plate 21 and plate 24 on the foot bar 13 are in place, a matrix 26 can be rolled over or engaged with the type forms 15 in the manner shown. When it is desired to make a proof, both of the 5 plates 21 and 24 on the frame and foot bar respectively are removed by lifting same, thereby disengaging the dowel pins 22 and 25 from their respective sockets 22' and 25'. The type forms 15 in the chase may now be inked for the customary proof.

It will thus be seen that by means of the present invention one instrumentality or chase may conveniently serve two purposes hitherto requiring two separate chases.

15 I am aware that the invention may be embodied in other specific forms without departing from the spirit or essential attributes thereof, and I therefore desire the present embodiment to be considered in all respects as illustrative 20 and not restrictive, reference being had to the appended claims rather than to the foregoing description to indicate the scope of the invention.

What I claim is:

1. In a device of the kind described, the combination of a frame adapted to receive type forms, means adjustably secured to said frame and operatively engageable with type forms arranged therein, and other means simultaneously coacting with the frame and first mentioned means 30 when applied to the upper surfaces thereof for adapting the device to serve for preparing matrices.

2. In a device of the kind described, the combination of a frame, a quoin, side and foot bars 35 adjustably secured to said frame, and means detachably securable to said frame and foot bar for adapting the device to prepare matrices when fastened to the frame, and permitting same when the means are removed, to prepare proofs.

40 3. In a device of the kind described, the combination of a frame, a plurality of means adjustably secured to the frame for operatively engaging type bodies securable in the said frame, and members optionally engageable with said frame and one of said means for converting same 45 from a thick chase to a thin chase.

4. In a chase of the kind described, the combination of a frame, members for engaging type forms adjustably secured within the frame, and 50 means detachably securable to said frame and one of said members for increasing the thickness of same sufficiently to make matrices and then to make a proof when removed from the frame.

55 5. In a device of the kind described, the combination of a frame, means mounted in said frame and adjustable by members rotatably secured thereto, for engaging type forms, and other means for adapting said frame and means to serve alternately as a thick chase for preparing matrices and as a thin chase for making proofs.

6. In a device of the kind described, the combination of a frame, a quoin, side and foot bars secured to said frame, and means simultaneously 65 coacting directly with the frame and foot bar when applied thereto for rendering said device operative for preparing matrices and for preparing proofs when removed therefrom.

7. In a device of the character described, the 70 combination of a frame, a quoin, side and foot bars, means for adjustably arranging said quoin and bars, and means detachably securable to the frame and at least one of said bars for converting said device from a chase suitable for 75 receiving and preparing a matrix to a chase suit-

able for making a proof from type forms securable within the frame.

8. A device of the kind described, comprising the combination of a frame, a quoin adjustably mounted in said frame and coactingly engaged with a side bar, mounted in said frame, a foot bar secured within the frame and adjustable therein by means connected thereto and threadedly engaged in the frame, and cover members detachably mountable on said frame and foot bar for adapting the device to prepare, in combination with type forms securable in the frame, a matrix, and to prepare, when the said cover members are removed, a proof.

9. In a device of the kind described, the combination of a frame, members for engaging type forms adjustably secured within the frame for accommodating forms of different sizes, and means detachably securable on marginal portions of said frame and on one of said members in superposed relation thereto for increasing the effective thickness of same sufficiently to make matrices and then to make a proof when removed from the frame.

10. In a device of the kind described, the combination of a frame, members for engaging type forms adjustably secured within the frame for accommodating forms of different sizes, means securable to said frame and one of said members for increasing the effective thickness of same, 30 when applied thereto, sufficiently to make matrices, and then to make a proof when removed from the frame, and other means for aligning the first-mentioned means with the frame and the last-mentioned one of said members.

11. In a device of the kind described, the combination of a frame, movable members for engaging type forms adjustably secured within the frame, means detachably securable to said frame and one of said members in superposed relation 40 thereto for increasing the thickness of same sufficiently to make matrices when applied thereto, and then for decreasing the thickness sufficiently to make a proof when removed from the frame, and other means including dowel pins for aligning the first-mentioned means in correct register with the frame and the last-mentioned one of said members.

12. In a printer's chase, a frame, an adjustable form engaging member adapted to hold the printing form for making a proof, means adapting the chase for use in making a matrix, including means for increasing the effective height of the frame, and means for increasing the effective height of the adjustable member.

13. In a printer's chase, a frame, an adjustable form engaging member adapted to hold the printing form for making a proof, means adapting the chase for use in making a matrix, including means for increasing the effective height of the frame, and means for increasing the effective height of the adjustable member, said means for increasing the effective height of the frame and of the adjustable member being provided with means for aligning them with the frame and the member respectively.

14. In a printer's chase, a frame adapted to hold a printing form for making a proof, means separably secured to the frame for increasing the effective height of same for making a matrix, and other means for adapting the frame to operatively retain the first mentioned means thereon when in use.
